UNITED STATES PATENT OFFICE.

JAKOB WIKSCHTRÖM, OF DUSSELDORF, GERMANY.

KNIFE FOR CUTTING THE POINTS OF WIRE-TACKS AND NAILS.

Application filed December 30, 1926, Serial No. 158,109, and in Germany April 3, 1295.

My invention relates to a knife for cutting the points of wire-tacks and nails in such a manner that no waste results.

Knives serving the same purpose are already known in different constructions.

The essential novelty according to the invention consists in the peculiar arrangement of several knives at the surface of a round bar in such a manner that by a rotation of 10 the bar through a certain angle each time another knife may be brought into the working position, a free space for the passage of the wire being each time at the face of the round bar opposite the knife. The cutting 15 edges converging to the center are arranged at a greater distance from each other so that damages of one knife cannot influence the other knives situated at a considerable distance which would be the case if the cutting 20 edges would be close together.

The cutting edges do not quite meet each other but terminate before their meeting at a depression formed in the center of the round bar, so that in known manner the inserted 25 wire will not be perfectly cut by the abutting cutting edges. The bevel provided in front of the cutting edges on the one hand and the faces arranged between the cutting edges on the other hand cause a longitudinal 30 tensile strain upon the wire whereby the wire portion not separated will be pulled off the wire point.

By this means further tearing or longitudinal splitting of the wire above the cutting 35 edges will be prevented during the cutting of the point even if the material is too hard, too brittle or tends to crack. As in consequence of the splitting the nail head could not be pressed together waste always 40 resulted hitherto.

All these draw-backs are obviated by the new knife and goods free of defects are obtained even if material of low standard is used.

In the accompanying drawing a knife according to the invention is shown by way of example. Fig. 1 is a front elevation of the knife. Fig. 2 shows two knives in section with a piece of wire to be cut between them. 50 Fig. 3 is a perspective view of a knife. Fig. 4 illustrates a piece of cut wire and Fig. 5 is a section taken on line 5-5 of Fig. 4. In this view the separated nail point is indicated in dotted lines.

55 Each knife has two cutting edges 1 and 2 converging at an acute angle the roof-

shaped faces of which extend inwardly and outwardly. According to the example shown three such cutting edge pairs are arranged in regular distance from each other 60 on the surface of a round bar *f*, so that there are three knives having the cutting edges 1, 2, 1', 2' and 1'', 2'' respectively. Between the cutting edges are two faces *a*, *b*; *a'*, *b'* and *a''*, *b''* respectively serving the purpose 65 of forming the nail point. Outwardly the cutting edges are defined by faces *c*, *c'*, *c''* in such a manner that a depression is formed by the face *c* between the cutting edges 1, 2', by the face *c'* between the cutting edges 1', 2'' and by the face *c''* between the cutting 70 edges 1'', 2. The depression so formed serves for the reception of the wire *d* to be cut as shown in Fig. 2 and in dotted lines in Fig. 1.

75 The center portion *e* of the round bar-tool is hollowed or excavated in such a manner that the diameter of this excavation is a little greater than the diameter of the circle in which would lie the points of the converging cutting edges 1, 2; 1', 2' and 1'', 2'' respectively of the three knives, so that the two cutting edges of the several knives terminate at the points 3, 4; 3', 4' and 3'', 4'' respectively.

80 At point 3 the faces *a* and *c* and at point 4 the faces *b* and *c''* meet and correspondingly at point 3' the faces *a'* and *c'*, at point 4' the faces *b'* and *c*, at point 3'' the faces *a''* and *c''* and at point 4'' the faces *b''* 85 and *c'*. In this manner a free space communicating, as shown in Fig. 3, with the excavation *e* is formed between the points 3, 4; 3', 4' and 3'', 4'' respectively. The center line of the faces *a*, *b* between the cutting edges meets with the excavation *e* at a point 5 which lies lower than the points 90 3 and 4. The points 5' and 5'' of the two other knives are arranged in the same manner.

100 The wire portion between the points 3, 5, 4 will therefore not be influenced by the cutting edges 1, 2.

In Fig. 5 the nail point cut from the wire is designated 6 whereas 7 and 8 are the flaps 105 between which the faces 9 are lying.

If a piece of wire is inserted between the knives, as shown in Fig. 2, the abutting edges 1 and 2 angularly cut the wire. The portion 110 of the wire lying in between the cutting edges 1, 2 is formed by the faces *a*, *b* to the point 6, the center of the wire, that is the

middle portion lying between the points 3 and 4, however, still remaining in connection with the cut wire, as the cutting edges do not quite meet each other.

5 The point 6 is held in the space formed by the faces *a*, *b*. The bevel behind the point 5 formed by the excavation *e* pulls the wire portion carrying the cut out flaps 7, 8 off the firmly held wire point in the direction of the arrow indicated in Figs. 4 and 5.

The center portion of the wire which is not cut forms a reinforcement preventing the tearing of the wire which otherwise is caused by the outer faces of the cutting edges 1, 2 15 acting as a wedge when using hard or brittle material. The lateral wedge action is prevented as during cutting the tension is effected by the bevel of the excavation *e* in the direction of the wire, whereby at the same time the flaps 7, 8 are pulled away from the outer faces of the cutting edges 1, 2.

The new knife arrangement also allows the provision of knives of different shape on one and the same round bar so that by 25 a simple rotation of the round bar one or the other knife construction is caused to be brought in the working position, whereby it is possible, without any difficulty, to manufacture in one and the same machine nails 30 with different shape of points. The change of shape may consist in this that instead of nails having angular points nails provided with rounded points may be made in which case it is only necessary that the faces *a* and *b*, converging in the example shown under 35 an acute angle, merge into each other so that a semi-circular conical trough is formed between the cutting edges 1, 2. The length of the nail point also may differently be 40 chosen for the single knives, as, on account of the absolutely independent arrangement of the knives on the face of the round bar and the excavation *e* in the center portion, it does not matter that for one knife the 45 points 3, 4 and 5 are arranged nearer the center than for another knife.

Instead of three knives as in the example illustrated four and more knives also may be provided whereby it is only necessary that 50 in the extension-line of each knife a free space for the wire is present which results of itself by the outer faces of each knife.

To facilitate the adjustment of the knives in their working position the round bar may 55 be provided with flattened portions *f* fitting in correspondingly shaped journals so that

on rotating of the bar the cutting edges of the new knife automatically come into the proper position. Notches, holes or the like *g* may also be provided to facilitate the proper 60 selection on turning the bar.

What I claim is:

1. A wire cutting die comprising a cross sectionally circular rod having a depressed cross sectionally central portion and provided with a plurality of radially disposed knives formed on one end thereof and recesses formed between each of the knives, said knives having their respective inner ends terminated at points outwardly of said central portion of the rod and each of said recesses lying diametrically opposite its corresponding knife, whereby to permit lateral introduction of a wire over said opposed recesses and their respective knives. 75

2. A wire cutting die comprising a cross sectionally circular rod having a depressed cross sectionally central portion and provided with a plurality of radially disposed knives formed on one end thereof and recesses formed between each of the knives, said knives having each inwardly converging cutting edges and being of substantially V-shaped cross section, the inner ends of the cutting edges of the knives terminating at 85 points outwardly of said central portion of the rod and each of said knives being arranged substantially intermediately of two of such recesses and diametrically opposite another of the same, whereby to permit lateral introduction of a wire over said opposed recesses and their respective knives. 90

3. A wire cutting die comprising a cross sectionally circular rod having a depressed cross sectionally central portion and provided with a plurality of radially disposed knives formed upon one end thereof and a corresponding number of recesses formed between each of the same, each of said knives including relatively opposed inwardly converging cutting edges, the inner ends of which terminate outwardly of said central portion of the rod and said knives being each of substantially V-shaped inwardly converging formation and being arranged substantially diametrically opposite their respective recesses, whereby to permit lateral introduction of a wire over said opposed recesses and their respective knives. 100 105

In testimony whereof I affix my signature.

JAKOB WIKSCHTRÖM.
